UNITED STATES PATENT OFFICE.

WILLIAM GERHARDT, OF NEW YORK, N. Y.

DESIGN FOR A SHIRT-PATTERN.

SPECIFICATION forming part of Design No. 31,775, dated October 31, 1899.

Application filed August 11, 1899. Serial No. 726,943. Term of patent 14 years.

To all whom it may concern:

Be it known that I, WILLIAM GERHARDT, of the city of New York, borough of Manhattan, in the county and State of New York, 5 have invented and produced a new and original Design for a Shirt-Pattern, of which the following is a specification, reference being had to the accompanying drawing, forming a part thereof, which represents a plan of my 10 design.

The design as here shown presents the pattern with the essentially straight side edges *a* and the top edge showing gore-like incisions *b*, between which shows a concave *c* and out 15 of which show straight edges *e*, respectively running into concaves *f*.

The design further presents the bottom edge of the pattern showing the middle portion *d* cut in or raised above the end portions.

The essential features of the design consist 20 in the approximately straight side edges *a* and the top edge showing gore-like incisions *b*, between which shows a concave *c* and outward of which show straight edges *e*, respectively running into concaves *f*.

I claim—

The design for a shirt-pattern, herein shown and described.

WILLIAM GERHARDT.
